UNITED STATES PATENT OFFICE.

CHARLES O. PEARSON, OF NEW YORK, N. Y.

ELEVATOR.

1,114,180.

Specification of Letters Patent.

Patented Oct. 20, 1914.

Application filed April 14, 1903. Serial No. 427,052.

To all whom it may concern:

Be it known that I, CHARLES O. PEARSON, a citizen of the United States, and a resident of the borough of Brooklyn, county of 5 Kings, city and State of New York, United States of America, have invented certain new and useful Improvements in Elevators, of which the following is a specification.

My invention relates to elevators and especially to certain constructions and arrangements which I have devised for insuring the safe operation of such apparatus.

I will describe my invention in the following specification and point out the novel 15 features thereof in claims.

Referring to the drawings, Figure 1 is a front elevation of an elevator hoisting apparatus and associated parts together with certain electrical apparatus and circuits 20 forming a part of the elevator. Fig. 2 is a side elevation, partly in section, of the hoisting apparatus shown in Fig. 1. Fig. 3 is a sectional side elevation of one of the overhead sheaves shown in Fig. 1. Fig. 4 is a 25 side elevation of an elevator apparatus similar to that illustrated in Fig. 1, showing on a smaller scale a different arrangement of the parts. Fig. 5 is a sectional end elevation of some of the parts shown in Fig. 4, the section being taken on the line 5—5 of Fig. 4. Fig. 6 is a similar view on a smaller scale of like parts somewhat differently arranged. Fig. 7 is a side elevation of another type of elevator hoisting engine with 35 its connected car and counterweight showing the present invention applied thereto. Fig. 8 is a sectional end elevation of certain of the parts shown in Fig. 7, the section being taken on the line 8—8 of Fig. 7. Fig. 9 40 is a sectional side elevation of a modified form of the driving sheave and auxiliary sheave of the elevator hoisting apparatus which is shown in Figs. 1 and 2. Fig. 10 is a front elevation of a portion of an elevator 45 car with a safety device thereon, together with certain connections between the safety device and the hoisting ropes or cables, and the auxiliary safety rope which is used in this system. Fig. 11 is a side elevation of

this car and safety device and its connected 50 parts. Fig. 12 is a bottom plan view of the car safety device. Fig. 13 is a front elevation, and Fig. 14 is a side elevation, partly in section, of a counterweight with a safety device thereon, together with its connected 55 parts.

Like characters of reference designate corresponding parts in all of the figures.

10 designates the base or foundation of the elevator hoisting engine.

11 is the motor mounted upon this base. On one side of the motor and affixed to its shaft is a traction or driving sheave 12. A 60 brake-pulley 13 is affixed to the motor shaft on the opposite side of the motor.

14 and 15 are the bearing pedestals for the motor shaft.

16, 17 are brake-shoes pressed against the 65 brake-pulley 13 by spring 17 and arranged to be released therefrom by an electromagnet 70 or solenoid 18 whenever the latter is energized.

20 designates an auxiliary sheave situated directly below the traction sheave 12. This auxiliary sheave is loosely journaled in a 75 lever 21 which is pivoted at 21^a in a bracket 22 depending from the base 10. The free end of this lever is supported by a spring 23 which is held in place by a stationary rod 24 and which may be adjusted by means of 80 nuts 25.

26 is a brake-member arranged with two braking surfaces which are so constructed that they may act under certain conditions upon both the traction sheave 12 and the 85 auxiliary sheave 20. This braking member normally rests upon the periphery or flanges of the auxiliary sheave 20 and is held in place by a pivoted arm 27.

30 designates one or more hoisting ropes 90 or cables which, after passing under the traction sheave 12, are carried up over a pair of sheaves 31 and 32 situated at the upper end of the elevator shaft. Thence these ropes or cables pass down to the car 40 and 95 the counterweight 50, to both of which they are connected.

33 is an auxiliary safety rope which is

also connected with both the car and counterweight. This safety rope, in the arrangement shown in Figs. 1 and 2, is carried down under the auxiliary sheave 20 somewhat loosely. The flange of this auxiliary sheave is constructed to form a deep annular groove 28 for the purpose of receiving and guiding this rope. If more than one of these auxiliary safety ropes are used the flange of the sheave 20 may be provided with a wider rope groove corresponding in width with the number of safety ropes as is shown in Fig. 9.

+ and — designate mains from a suitable source of electrical supply which, after passing through a safety cut-out switch 60, are connected with one of the field terminals of motor 11 and with certain stationary contacts of an electrically actuated reversing switch 61. The positive or + main is also connected by a conductor 62 with the lever 63 of a controlling switch in the car. The negative or — main is connected through solenoid windings 64 and 65 of solenoids which form part of the reversing switch mechanism, and conductors 66 and 67 with stationary contacts 68 and 69 of the car-switch. It may be seen that when the lever 63 is moved to the right, a circuit is closed thereby through the solenoid winding 64 and the left-hand portion of the reversing switch which is actuated thereby. This will close circuits through the fields of the motor, through the armature of the motor in one direction, and also through the winding of the brake magnet 18 which is shown connected across the armature leads by dotted lines 19. This will cause the motor to revolve in one direction to drive the car through traction sheave 12 and hoisting ropes 30. This operation will continue until the circuits are broken by the operator returning the car-switch lever to its central position or by other means. When this is done, the motor current will be cut off, the brake applied, and the apparatus will come to rest. Similarly, when the car-switch lever 63 is moved to the left, the right-hand portion of the reversing switch will be actuated to close the motor and brake circuits. But in this case the motor armature will receive current in the opposite direction, and its rotation and the movement of the car will be opposite to that obtained by the previously described operation.

During the above operations, the auxiliary safety rope and its associated parts perform no function. The safety rope is connected in parallel with the hoisting ropes and runs with them, but it is not under tension and therefore does not assist them in their work. If however, the hoisting ropes break, become detached from their anchorages, or become unduly elongated from any cause, the weight of the car and counter-

weight is then thrown onto the auxiliary safety rope. The first effect of this will be to sustain these parts and prevent them from falling. The strains put upon the rope 33 by the weight of the car and counterweight 70 will pull the sheave 20 upward until this movement is checked by the brake-member 26 which will be forced thereby against the driving sheave 12. This will retard and stop the rotation of both of the sheaves 12 75 and 20 and gradually bring the various parts of the apparatus to rest. The upper surface of the brake-member 26 is preferably made, as shown in the drawings, to engage directly with the hoisting cables 30 and to act 80 through them on the traction sheave 12. Thus it not only produces the required braking effect upon the driving sheave, but it also holds the cables and the parts which they still support after a break has occurred.

In Fig. 1, a flexible connection 29 is shown between the free end of the pivoted lever 21 and the safety cut-off switch 60. It is obvious that these parts are so arranged that whenever the lever 21 is actuated by the auxiliary safety rope, as above described, the switch 60 will be pulled open thereby to cut off the electrical supply from the motor and the brake, thus adding materially to the effective working of the apparatus.

In Fig. 4 the motor is geared to drive a pair of traction sheaves 12^A and 12^B over which the hoisting cables 30 are run in the 100 usual manner. In this case the auxiliary safety rope 33^A is connected with the car and counterweight as before, but it is supported by two auxiliary overhead sheaves 31^A and 32^A mounted upon a lever 34, one 105 end of which is pivoted at 35 and the other end of which is supported by a compression spring 36 of sufficient strength to maintain the weight of the lever, the auxiliary sheaves and the safety rope. A brake-member 26^A is placed between the sheaves 31 and 31^A. One end of this brake-member is pivoted at 37 and its other end upheld by a spring 38 so that it normally remains midway between the peripheries of the two sheaves. Another brake-member 26^B is similarly held between the sheaves 32 and 32^A by a spring 39. It may be seen that in case the weight of the car and counterweight is thrown upon the safety rope the effect of the springs 36, 38 115 and 39 will be overcome and the sheaves 31^A and 32^A will be pulled down against the sheaves 31 and 32 with the brake-members between them. The effect of this will be similar to that described in connection with the other arrangement of the parts and the car and counterweight will be gradually brought to rest.

The arrangement shown in Fig. 6 is that used when the motor 11 and the driving 120

sheave 12 are placed at the top of the elevator shaft. The auxiliary safety rope 33 is here led over a sheave 31^B directly above the traction sheave 12 upon a pivoted lever 34 with the brake-member 26^C between them. The latter is shown supported in this case upon two compression rings 38^A.

The operation of this device is obvious from the former descriptions.

10 In Fig. 7 the motor 11 is geared to drive a winding drum 12^C. One of the hoisting ropes 30^A is secured to this drum and to the car 40 while another hoisting rope 30^B is connected with the counterweight and with 15 the drum around which it is wound in the opposite direction. The auxiliary safety rope 33 is led under the brake-member 26^B, under the winding drum, although it is evident that the arrangement of overhead 20 sheaves and brake-members illustrated in Fig. 4 may, if desired, be used in conjunction with this type of elevator.

Referring now to Figs. 10 and 11, I will show the preferred manner of connecting 25 the ropes to the car 40. The hoisting ropes 30 may be directly affixed to any desired portion of the car, as, for example, the cross-head to which they are shown fastened in the drawings. The auxiliary safety rope 33 is, however, connected with a lever 41 which is pivoted to the car at 41^A. The spring 41^B interposed between the top of lever 42 and the cross-head of the car tends to keep the lever and its connected parts in 35 their lowermost positions. This spring is of sufficient strength to be unaffected by the usual pulling strains upon the rope 33 caused by the running of the car. 42 is a vertical rod depending from the outer end of lever

40 41. The lower end of this rod is constructed to form a flat blade which fits loosely into the periphery of a disk 43 which is affixed to a rotatable shaft 44. 45 designates gripping jaws which are pivotally connected with the car and arranged to be forced onto the elevator guide-rails 40^A, by means of a powerful spring 46, acting through jaw actuating members 47. The latter are mounted upon levers 48 which are pivoted 50 at 48^A, and their outer ends are connected with the rotatable disk 43 by means of connecting rods 49 and the shaft 44.

The above parts comprise a car safety device which may be set by compressing the 55 spring 46 until the parts may be moved back into the positions illustrated in the drawings, when the flat blade of the lower end of vertical rod 42 may be led into the groove in the periphery of the disk 43 to lock and hold the parts as shown. Now, whenever the weight of the car or counterweight comes onto the auxiliary safety rope 33, the lever 41 and rod 42 will be pulled up thereby and the spring 46 will be released 60 to force the clamping jaws onto the guide-

rails 40^A. This will obviously have a braking effect upon the movement of the car and tend to hold the car on the guide-rails.

A similar safety device to that above described is connected with the counterweight 70 50 to clamp it to the guide-rails 50^A, and in Figs. 13 and 14 the reference numerals 51-55 and 59 designate similar parts to those above specifically pointed out in connection with the car. The operation of this counterweight safety device is also similar to that above described, and it may be seen that the two safety devices act simultaneously to clamp their respective parts of the apparatus to the guide-rails and that at the same time the motive power is shut off from the hoisting engine and a powerful braking force is applied to the auxiliary safety rope and to so much of the hoisting ropes as remain intact and connected with their connected parts.

The object of this invention is to provide an elevator system with safety appliances which are thoroughly reliable and which will prevent the falling of the car or its 90 counterweight without adding undue strain to the structure or apparatus. In this connection it is pointed out that there is a positive connection between the car and its counterweight so that the weight of neither has to be sustained alone upon the guides. The safety appliances will act simultaneously at all the important portions of the system, but none of them is too sudden in its effect to put undue strains upon the apparatus or 100 to produce serious jarring to passengers upon the car.

This invention is especially adaptable for use in conjunction with traction or rope drive elevators.

This type of elevator apparatus has many advantages over other systems, but hitherto has been open to the serious objection of being more dangerous than others. The invention is also adaptable to other types of elevators as I have shown and described, and is also capable of many modifications such, for example, as those illustrated in the drawings.

What I claim is:—

1. In an elevator, a hoisting apparatus comprising a driving sheave, a car, a counterweight, a hoisting rope connecting the car and the counterweight with the driving sheave, a safety rope connected with the car and counterweight, a second sheave around which the safety rope is arranged to run in alignment with the driving sheave, and a brake-member between said sheaves.

2. In an elevator, a hoisting apparatus 125 comprising a driving sheave, a car, a counterweight, a hoisting rope connecting the car and the counterweight with the driving sheave, an idle safety-rope connected with the car and the counterweight, a second 130

- sheave around which the safety rope is arranged to run, a movable bearing for said sheave, and a brake-member between the driving sheave and the safety rope sheave; 5 said second sheave and brake-member being so arranged that a tensional strain upon the safety rope may move the position of the safety rope sheave and brake-member to apply the brake-member to both of the sheaves.
- 10 3. In an elevator, a hoisting apparatus comprising a driving sheave, a stationary bearing therefor, a car, a counterweight, a hoisting rope connecting the car and the counterweight with the driving sheave, an idle safety rope connected with the car and the counterweight and running with them, a second sheave around which the safety rope is arranged to run, a movable bearing for said second sheave, and a brake-member between the driving sheave and the second sheave, said second sheave and brake-member being so arranged that a tensional strain upon the safety rope may move the positions of the second sheave and the brake-member 15 to apply the latter to both of the sheaves.
- 20 4. In an elevator, a hoisting apparatus comprising a driving sheave, a car, a counterweight, a hoisting rope connecting said car and counterweight with the driving sheave, and a safety rope arranged to suspend the car and counterweight and to brake the hoisting apparatus if the hoisting rope should fail.
- 25 5. In an elevator, a hoisting apparatus comprising a driving sheave, a brake therefor, a car, a counterweight, a hoisting rope connecting the car and counterweight with the driving sheave, and an idle safety rope arranged to suspend the car and counterweight and to apply said brake to the driving sheave if the hoisting rope should fail.
- 30 6. In an elevator, a hoisting apparatus comprising a motor and a driving sheave, a brake for said driving sheave, a car, a counterweight, a hoisting rope connecting the car and counterweight with the driving sheave and driven through said sheave by the motor, and a slack safety rope indirectly driven by said motor and arranged to suspend the car and counterweight, and to apply said brake to the driving sheave if the hoisting rope should fail.
- 35 7. In an elevator, a car, a counterweight, a hoisting rope connecting said car and counterweight, a sheave around which said rope is arranged to run, a safety rope connected with the car and the counterweight, a second sheave around which the safety rope is arranged to run, a brake member between said sheaves, said brake member being arranged to engage with the hoisting rope upon its sheave and with the safety rope sheave, said safety rope sheave and brake-member being arranged to be moved by the safety rope whenever tensional strain 40 is put upon it to thereby apply the brake-member to the hoisting apparatus through the safety rope and to the second sheave.
- 45 8. In an elevator, a hoisting apparatus comprising a driving sheave, a stationary bearing therefor, a car, a counterweight, a hoisting rope connecting the car and the counterweight with the driving sheave, an idle safety rope connected with the car and the counterweight and running with them, a second sheave around which the safety rope is arranged to run, a movable bearing for said second sheave, and a brake-member between the driving sheave and the second sheave, said brake-member being arranged to engage with the hoisting rope upon the driving sheave and with the second sheave; 50 said second sheave and brake-member being arranged to be moved by the safety rope whenever tensional strain is put upon it to thereby apply the brake-member to the driving sheave through the hoisting rope and to said second sheave.
- 55 9. In an elevator, a car, a safety device on the car, a counterweight, a safety device on the counterweight, a hoisting rope supporting said car and counterweight, a driving sheave around which said rope is arranged to run, a safety rope connecting the car safety device and the counterweight safety device, a second sheave in alignment with said driving sheave around which the safety rope is arranged to run, a single brake-member between and in alignment with said sheaves having directly opposed friction surfaces, and means actuated by the safety rope whenever tensional strain is put upon it for actuating the safety devices and for applying the brake-member to both of the sheaves.
- 60 10. In an elevator, a hoisting apparatus comprising a driving sheave, a stationary member therefor, a car, a safety device on the car, a counterweight, a safety device on the counterweight, a hoisting rope connecting the car and the counterweight with the driving sheave and arranged to support said car and counterweight, an idle safety rope connecting the car safety device and the counterweight safety device, and running with the car and counterweight, a second sheave around which the safety rope is arranged to run, a movable bearing for said second sheave, a brake-member between the driving sheave and the second sheave, and means actuated by the safety rope whenever tensional strain is put upon it for actuating said safety devices and for moving the positions of the second sheave and the brake-member to apply the latter to both of said sheaves.
- 65 11. In an elevator, a hoisting apparatus comprising a motor, a car, a counterweight, a hoisting rope connecting said car and the counterweight with the driving sheave, an idle safety rope connected with the car and the counterweight and running with them, a second sheave around which the safety rope is arranged to run, a movable bearing for said second sheave, a brake-member between the driving sheave and the second sheave, and means actuated by the safety rope whenever tensional strain is put upon it to thereby apply the brake-member to the driving sheave through the safety rope and to the second sheave.

counterweight, a sheave around which said hoisting rope is arranged to run, said sheave being driven by the motor, a safety rope connected with the car and the counterweight, a sheave on which the safety rope is arranged to run, a brake-member between said sheaves, and means actuated by the safety rope for cutting off power from the motor and applying said brake member to the sheaves whenever tensional strain is put upon the safety rope.

12. In an elevator, a hoisting apparatus comprising a motor and a driving sheave, a car, a counterweight, a hoisting rope connecting said car and counterweight with the driving sheave, a safety rope arranged to suspend the car and counterweight and to brake the hoisting apparatus if the hoisting rope should fail, and means actuated by said safety rope for cutting off power from the motor.

13. In an elevator, a hoisting apparatus comprising a motor and a driving sheave, a brake for said motor, a car, a counterweight, a hoisting rope connecting the car and counterweight with the driving sheave, an idle safety rope arranged to suspend the car and counterweight and to apply said brake to the driving sheave, and means actuated by said safety rope for cutting off power from the motor if the hoisting rope should fail.

14. In an elevator, a hoisting apparatus comprising an electric motor and a driving sheave, a car, a hoisting rope connecting the car with the driving sheave and sustaining the car, an idle safety rope associated with said parts and arranged to sustain the car if the hoisting rope fails, and means actuated by said safety rope for cutting off the electrical power from the motor whenever tensional strain is put upon the safety rope.

15. In an elevator, a hoisting apparatus comprising an electric motor, a driving sheave, and an electrically actuated brake for said apparatus; a car, a counterweight, a hoisting rope connecting the car and counterweight with the driving sheave, a safety rope arranged to suspend the car and counterweight if the hoisting rope should fail, and means actuated by said safety rope for cutting off the power from the motor and for applying said brake to the driving sheave.

16. In an elevator, a hoisting apparatus comprising an electric motor, a driving sheave, and an electrically actuated brake for said apparatus; electrical circuits for the motor and brake, a switch in said circuits, a car, a counterweight, a hoisting rope connecting the car and counterweight with the driving sheave and driven through said sheave by the motor, a slack safety rope also driven by said motor and arranged to sus-

pend the car and counterweight if the hoisting rope should fail, and means actuated by said safety rope for opening said switch to apply said brake to the driving sheave and to break the circuit to the motor.

17. In an elevator, a hoisting apparatus comprising a motor, a car, a hoisting rope connecting the car with the hoisting apparatus, a safety device on the car, a slack safety rope connecting the car safety device with the hoisting apparatus and arranged to suspend the car, cut off the power from the motor and apply said safety device if the hoisting rope should fail.

18. In an elevator, a hoisting apparatus comprising a motor, a car, a counterweight, a hoisting rope connecting the car and the counterweight with the hoisting apparatus, a safety device on the car, a safety device on the counterweight, a slack safety rope connecting the car safety device with the counterweight safety device and arranged to suspend the car, cut off the power from the motor and apply said safety devices if the hoisting rope should fail.

19. In an elevator, a hoisting apparatus comprising an electric motor and a driving sheave, a car, a safety device on the car, a counterweight, a safety device on the counterweight, a hoisting rope connecting said car and counterweight with the driving sheave, a safety rope connecting the car safety device and the counterweight safety device, a second sheave upon which the safety rope is arranged to run, a brake-member between said sheave and the driving sheave, said second sheave and brake-member being arranged to be moved by the safety rope whenever tensional strain is put upon it to thereby apply the brake-member to both of the sheaves, and means actuated by the safety rope for actuating the safety devices and for cutting off power from the motor.

20. In an elevator, a hoisting apparatus comprising an electric motor, a driving sheave, a stationary bearing therefor, an electrically controlled brake, circuits for the motor and the brake; a car, a safety device on the car, a counterweight, a safety device on the counterweight, a hoisting rope connecting the car and the counterweight with the driving sheave and arranged to support said car and counterweight, an idle safety rope connecting the car safety device and the counterweight safety device and running with the car and counterweight, a second sheave upon which the safety rope is arranged to run, a movable bearing for said second sheave, a brake-member between the driving sheave and the second sheave, said second sheave and brake-member being arranged to be moved and the safety devices arranged to be actuated by the safety rope whenever tensional strain is put upon

it to apply the brake-member to both of said sheaves and to stop the car and the counterweight, a cut-out switch for cutting off power from the motor and the brake, said safety device actuating means and cut-out switch being also actuated by the safety-rope.

In testimony whereof I have signed my name to this specification in the presence of two subscribing witnesses.

CHARLES O. PEARSON.
